UNITED STATES PATENT OFFICE.

WORCESTER HADDOCK, OF CINCINNATI, OHIO.

CABLE-RAILROAD SHEAVE.

SPECIFICATION forming part of Letters Patent No. 399,035, dated March 5, 1889.

Application filed June 9, 1888. Serial No. 276,600. (No model.)

To all whom it may concern:

Be it known that I, WORCESTER HADDOCK, a citizen of the United States, and a resident of Cincinnati, in the county of Hamilton, 5 State of Ohio, have invented certain new and useful Improvements in Cable - Railroad Sheaves, of which the following is a specification.

The object of my invention is to so construct a cable sheave and attachments that said sheave may be readily and quickly oiled without removal from the conduit, and yet admit of the same being removed for repairs, if so desired.

15 In the drawings accompanying this specification and forming a part thereof, Figure 1 is a central vertical cross-section through the sheave and set-collars, showing one preferable mode of attaching said collars to the shaft. 20 Fig. 2 is a view in side elevation of the sheave, the semicircular dotted lines at the bottom of the shaft showing the position of the oil-reservoir therein, also showing the top of one end of the shaft cut away when said shaft is 25 keyed to the journal-box in the conduit. Fig. 3 is a vertical cross-section taken through the bottom and side walls of the conduit and man - hole and the slot-rails, showing the sheave with attachments in position in said 30 conduit. Fig. 4 is a view in elevation, on an enlarged scale, of the collar shown at left hand in Fig. 3, said collar being provided with an oiling attachment. Fig. 5 is a view in elevation of the collar shown at right hand 35 in Fig. 3, showing an air-vent therein. Fig. 6 is a cross-section of the journal-box shown at left hand in Fig. 3, in which one end of the shaft is keyed.

While my invention is preferably used in 40 connection with a conduit constructed substantially as shown, the sheave and attachments may be used in connection with any form or construction of conduit that will admit of attachment of journal boxes or supports for the shaft to rest in.

The form of conduit shown (partially) in Fig. 3 forms the subject-matter of a separate application for Letters Patent, Serial No. 277,914.

45 Any desirable form of sheave may be employed having one or more grooves for the

cable to operate in, and is preferably cast with a central hub, A, circular at each end on its outer surface. The circular end portions of the hub rotate in the flanged portions 55 of the collars, as shown in Fig. 3.

The inner face of the hub A is provided with suitable bushing, a, made fast thereto to afford a more durable bearing-surface.

The sheave is supported by and rotates 60 upon the shaft D, which latter is rigidly attached to the side walls of the conduit and man-hole in any suitable manner, one mode being shown as follows: To one side of the conduit is formed a journal-box, H, the opening of which is vertically oblong to admit of the shaft being placed therein at an angle. At the opposite side of the conduit, near the bottom of the man-hole, is formed the journal-box I, which is open at top to admit of the 70 shaft being dropped therein. The shaft is prevented from rotating by means of the key 75 i, which is driven into the openings in the journal-box over the flat portion d' of the shaft D.

To properly adjust and oil the sheave on the shaft, I have provided the two set-collars B and C, which are attached to the shaft in any suitable manner, preferably by means of the set-screws d, as shown. The collars have 80 cast with them the circular flanges b and c, respectively, which overlap the circular end portions of the hub A, to prevent any dirt from working in between the bushing of the hub and the shaft. The washers e, inter- 85 posed between the ends of the hub and the collars, also assist to keep any dirt from working in onto the shaft, and also very greatly assist to prevent rattling or any to-and-fro motion of the sheave on the shaft. The col- 90 lars can be readily adjusted to take up any wear on the washers.

The collar B has an air-vent, b', made in it for the purpose of admitting air to the oil-reservoir E in the shaft to secure a ready flow 95 of oil therein.

The collar C has an inner circular recess, c', as shown in Fig. 1, which encircles the shaft at one end of the semicircular oil-groove E. To this collar is cast the hollow lug F, 100 the opening f' in said lug connecting with the circular recess c' of the collar. To this lug F

is connected the pipe G, which latter preferably extends up to near the top of the man-hole and is covered with a suitable cap, as g. When desired to oil the sheave, the cap g is removed and the oil poured into pipe G, and from thence the oil flows into opening f', through the recess c', into the oil-reservoir E in the under surface of the shaft.

If desired, the pipe G and cap g may be dispensed with and the oil poured direct into the opening f' of lug F.

The shaft D, upon which the sheave rotates, has a semicircular longitudinal groove, E, in its under face, which serves as a reservoir for the oil. This reservoir being at all times filled with oil, and the sheave rotating around the same, serves to keep the bushing of the sheave and the shaft perfectly oiled.

The operation of my device is very accurate and reliable. It is simple in construction and affords a very convenient and economic means of oiling the sheaves without removal from the conduit, which feature is a very desirable one, and is quite a saving of time and money, especially on cable lines of any considerable length. The sheave and attachments are placed together in an operative position before being placed in the conduit. To place them in position in the conduit, the lid L of the man-hole is removed and the shaft of the sheave placed in the journal-boxes H and I, in the manner aforescribed. The key i is then driven to place in the journal-box I over the flat portion d' of the shaft, thus retaining the shaft firmly in the conduit in a non-rotatable position.

When desired to remove the sheave for repairs, all that is necessary is simply to drive the key i from place, when said sheave may be lifted from place through the man-hole in the conduit.

What I claim as new, and desire to secure by Letters Patent, is—

1. In combination with a cable sheave, a stationary shaft having a longitudinal oil-reservoir in its under or lower face, the collars B and C, attached to said shaft, the collar B, having an air-vent therein, and the collar C, constructed, substantially as described, for ad-

mitting oil to said reservoir in the shaft, and suitable means for supporting said shaft to the conduit.

2. In combination with a cable sheave, the shaft D, having the oil-reservoir E therein, collars B and C, set-screws d d, for attaching said collars to the shaft, washers e e, interposed between said collars and the ends of the hub, and suitable means for attaching said shaft to the conduit, substantially as set forth.

3. In combination with a cable sheave, the shaft D, having a longitudinal oil-reservoir therein, collars B and C, having overlapping flanges b and c, respectively encircling the end portions of the hub A, the collar B, having an air-vent therein, and the collar C, having an annular recess, c', on its inner portion, and lug F, cast with said collar C, and having an opening, f', leading to said recess c', substantially as set forth.

4. In combination with a cable sheave, the shaft D, having a longitudinal recess therein, collar B, having an air-vent, b', and suitable means for connecting said collar to the shaft, collar C, having the annular recess c' therein, lug F, having opening f', said lug being cast with said collar C, pipe G, inserted or attached to said lug, and having a suitable cover, g, and suitable means for connecting the shaft to the conduit, as and for the purposes set forth.

5. In combination with a cable sheave, shaft D, having an oil-reservoir, E, collar B, having an air-vent, b', collar C, having annular recess c', and lug F, cast thereto, set-screws d, washers e e, pipe G, and suitable means for securing said shaft in the conduit in a non-rotatable position, substantially as set forth.

6. In combination with a cable sheave, a shaft, and oiling attachments constructed, substantially as set forth, the journal-boxes H and I, formed with the walls of the conduit, and key i, inserted into the journal-box I over the flat portion d' of the shaft, substantially as set forth.

WORCESTER HADDOCK.
